Atty.

UNITED STATES PATENT OFFICE.

EDWARD H. MOSHER, OF SOUTH PARIS, MAINE.

FOLDING TABLE.

1,233,389.

Specification of Letters Patent. Patented July 17, 1917.

Application filed June 24, 1916. Serial No. 105,541.

To all whom it may concern:

Be it known that I, EDWARD H. MOSHER, a citizen of the United States, residing at South Paris, in the county of Oxford and

5 State of Maine, have invented certain new and useful Improvements in Folding Tables, of which the following is a specification.

My invention relates to folding tables and it relates particularly to tables having 10 round or circular tops.

The object of the invention is to construct such a circular topped table which will be strong, easily folded and which may be cheaply built and put on the market.

15 With these ends in view my invention consists of the combination of parts hereinafter particularly described and set forth in the appended claims.

My invention will be readily understood 20 by reference to the accompanying drawing in which—

Figure 1 is a side elevation of the table fully opened.

Fig. 2 is a plan of the under side of the 25 table top with the legs open and one shown in section.

Fig. 3 is a side view of the table shown in a folded position.

Fig. 4 is a section on the line *xx* of Fig. 2. 30 Fig. 5 is a section on the line *yy* of Fig. 2 and

Fig. 6 is a view of one end of the cleat.

Like reference figures indicate like parts in all the views:

35 In the drawing 1 represents the table top which is preferably of wood so that it can hold screws and nails.

The table top rests when it is in its normal or open position directly on the upper 40 ends of two frames which cross each other preferably at right angles.

One of the frames is made up of legs 2, 2, and cross bars 3 and 4, the upper cross bar 3 being preferably a dowel. This frame is 45 hinged to the under side of the top by yielding hinges here shown as formed of wires 5. One end of each of the wires 5 is formed into an eye 6 which embraces one end of the dowel 3 and the opposite end is turned 50 up and enters an opening in the under side of the table top as shown in dotted lines Figs. 1 and 5.

The wires are firmly clamped to the under surface of the table near their outer ends by 55 clips 7 secured to the table by screws. The greater length of the wire thus acts as a

spring to pivot or hinge the dowel 3 and the frame to the table top but the tension of the spring constantly forces the table top down onto the end of the leg. 60

This frame may thus be turned down so that the legs are parallel with the table and forced firmly against it by the wire spring hinges.

The second frame consists of the legs 8 and 8^a with cross bars 9, 10. 65

The bars 3 and 9 and 4 and 10 are pivoted together where they cross by a pivot 11 which is preferably a dowel which passes up through the bars 4, 10, 9 and 3. 70

Thus one of the supporting frames having legs 8 and 8^a is pivoted to the other having legs 2 and 2^a and may be folded against the other as shown by dotted lines in Fig. 2 preparatory to turning down the legs 2. 75

The legs 8 and 8^a are held in their extended position so that they will automatically lock in place when they are opened and so that they may be easily released when the table is to be folded. 80

One side of each of the legs 8 and 8^a is held in open position by a cleat 12 which is secured to the under side of the top and extends centrally across the table top. The frame 8, 8^a crosses the cleat and at the 85 points where the legs contact, the cleat is cut away to form notches 13 to give it a fair contact with the edge of the cleat. One of the legs, 8^a is held in extended or open position by a wedge shaped piece 14 fastened 90 to the table top adjacent to the edge of the cleat and far enough away from it to form a recess into which the upper end of the leg 8^a will snap when the leg is opened out. 95 (See Fig. 4.)

It will be borne in mind that both the frames are forced constantly upward with a resilient pressure against the under side of the table top 1 by the spring hinges and when in opening the frame 8, 8^a the leg 8^a 100 strikes the inclined surface of the piece 14 it slides readily upward and snaps into the recess being held firmly in place by said hinges.

The table top is thus caused to rest on the legs 2, 2, 8 and 8^a when the table is open and when in use the legs being so locked that they cannot get loose. 105

When it is desired to fold the table, the leg 8^a is seized by the hand and pressed down while the top is slightly lifted lifting the leg out of its retaining recess between 110

the cleat 12 and the wedge 14 against the force of the springs 5.

The legs 8 and 8^a may now be folded against the legs 2, 2, swinging on the pivot 2 dowel 11 as shown in dotted lines Fig. 2 and the four legs may swing down with the hinges 5 as a center and fold against the table top, being held in place always by the tension of the wire spring hinges 5.

10 The table is opened or unfolded in a similar manner and the whole as described, constitutes a practicable and effective folding table well adapted to be manufactured by a wood working plant.

15 I claim:

1. In a folding table, the combination of a table top, two pairs of supporting frames on which the table normally rests, said frames crossing each other and being each 20 composed of two legs and connecting bars, a pivot for connecting the bars to adapt the frames to be folded horizontally together, a pair of spring wires forming 25 hinges connecting one of said frames to the table top, each wire being bent at one end to pivotally connect with one of the cross bars and stops having inclined surfaces over which the frame slides, against the pressure of said hinges, for holding the 30 other frame in its normal open position.

2. In a folding table, the combination of a table top, two pairs of supporting frames on which the table normally rests, said frames crossing each other and being each 35 composed of two legs and connecting bars, a pivot for connecting the bars to adapt the frames to be folded horizontally together, a pair of spring hinges connecting one of said frames to the table top and a stop for 40 automatically engaging and holding the other frame in its normal open position, said stop embodying a recess in which the upper end of the frame is held by the re-

siliency of the spring hinges and an inclined surface for guiding the frame into 45 said recess.

3. In a folding table, the combination of a table top, two pairs of supporting frames on which the table normally rests, said frames crossing each other and being each 50 composed of two legs and connecting bars, a pivot for connecting the bars, to adapt the frames to be folded horizontally together, a pair of spring wires forming 55 hinges connecting one of said frames to the table top, each wire being bent at one end to enter the table top, the opposite end encircling one of the connecting bars and being substantially in contact with one of the legs, a clip for securing said wire between its ends to the under side of the table top and stops having inclined surfaces over which the frame slides against the pressure of said hinges.

4. In a folding table, the combination of a 60 table top, two pairs of supporting frames on which the table normally rests, said frames crossing each other and being each composed of two legs and connecting bars, a pivot for connecting the bars, to adapt the 65 frame to be folded horizontally together, a pair of spring wires forming hinges connecting one of said frames to the table top, each wire being bent at one end to enter the table top, the opposite end encircling 70 one of the connecting bars, and being substantially in contact with one of the legs, a clip for securing said wire between its ends to the under side of the table top, screws 75 for holding said clip in contact with said 80 wire and stops having inclined surfaces over which the frame slides against the pressure of said hinges.

In testimony whereof I affix my signature.

EDWARD H. MOSHER.
